UNITED STATES PATENT OFFICE

149,951

DESIGN FOR A HAND LAMP SWITCH

Walter R. Kopp, New Haven, Conn., assignor to
Olin Industries, Inc.

Application February 24, 1947, Serial No. 137,120

Term of patent 14 years

(Cl. D48—24)

To all whom it may concern:

Be it known that I, Walter R. Kopp, a citizen of the United States, residing at New Haven, in the county of New Haven and State of Connecticut, have invented a new, original, and ornamental Design for a Hand Lamp Switch, of which the following is a specification, reference being had to the accompanying drawing forming a part thereof.

In the drawing,

Fig. 1 is a plan view of a hand lamp switch showing my new design;

Fig. 2 is a side elevation; and

Fig. 3 is an end elevation.

I claim:

The ornamental design for a hand lamp switch, as shown.

WALTER R. KOPP.
